ATTORNEY

UNITED STATES PATENT OFFICE.

DANIEL PIERSOL, OF LANCASTER, PENNSYLVANIA.

DESIGN FOR AN ORNAMENTAL FRAME.

SPECIFICATION forming part of Design No. 33,128, dated August 28, 1900.

Application filed December 2, 1899. Serial No. 739,045. Term of patent 8 years.

To all whom it may concern:

Be it known that I, DANIEL PIERSOL, a citizen of the United States, and a resident of Lancaster, in the county of Lancaster and

5 State of Pennsylvania, have invented and produced a new and original Design for an Ornamental Frame, of which the following is a specification, reference being had to the accompanying drawing, forming part thereof.

10 The figure of the drawing is a perspective view illustrating my design.

As shown in the drawing, the leading or material feature of my design consists of a frame A, having the shape or contour of a 15 heart, with elongated concaved surfaces B formed at intervals on the front of the frame, and the representation of a bow D at the top

and center of the frame. The edges a of frame A are raised and smooth, with interior corrugations a', while the part a² between 20 said edges is roughened.

Having described my invention, what I claim as new, and desire to secure by Letters Patent, is—

The design for an ornamental frame, as 25 herein shown and described.

In testimony whereof I have signed my name to this specification in the presence of two subscribing witnesses.

DANIEL PIERSOL.

Witnesses:

C. G. BASSLER,
Wm. R. GERHART.
